UNITED STATES PATENT OFFICE.

JOSEPH H. DILLON AND HOWARD H. FAIRWEATHER, OF COATESVILLE, PENNSYLVANIA, ASSIGNORS TO BETHLEHEM STEEL COMPANY.

CLOSURE.

Application filed June 1, 1925. Serial No. 33,967.

Our invention relates to manhole cover-plates for boilers and the like, and more particularly to the handle parts thereof.

Heretofore, cover-plates have been made of single pieces of pressed metal without handles and through which bolt holes or the like extend for holding bolts. These perforations weaken the cover-plate and leakage is liable to occur around the bolts. It is usually necessary to employ specially shaped bolts or special attaching means to clamp a manhole cover-plate to the side of a boiler.

One of the objects of our invention is to attach a handle to a cover-plate of this character in such a manner as to form a brace for the cover-plate, whereby, in its manufacture, thinner plate material may be used and whereby such a plate may be more easily carried or held in position when securing it to the side of a boiler.

Another object of our invention is to form the handle with T-slots, so that a bolt of ordinary form, instead of bolts of special design, may be used in securing the manhole cover-plate to a boiler.

Other objects of our invention will appear hereinafter.

Having thus given a general description of our invention, we will now, in order to make the same more clear, refer to the accompanying sheet of drawings in which like characters of reference indicate like parts:

Fig. 1 is a plan view of the front of our improved manhole cover-plate;

Fig. 2 is a longitudinal sectional view taken on line II—II of Fig. 1;

Fig. 3 is a transverse sectional view taken on the line III—III of Fig. 1;

Fig. 4 is a transverse sectional view taken on the line IV—IV of Fig. 1; and

Fig. 5 is a longitudinal sectional elevation taken on the line V—V of Fig. 1 and showing enough of the boiler casing and yokes to illustrate the application of our invention.

Referring to the drawings more in detail, the numeral 10 (Fig. 5) indicates the shell or casing of a boiler, having an oblong opening 11 surrounded by an integral flange 12. 13 is the cover plate for closing the opening 11.

This cover-plate has a flanged edge 14, which bears against the flange 12 of the boiler casing 10; and mounted between the two flanges

12 and 14 is a suitable gasket 15. The cover-plate 13 is made preferably of a single sheet of steel plate struck up between dies to the form shown clearly in the drawings.

The cover-plate 13 has a dome portion 17 extending outwardly from the flange; and the dome is provided with a central oblong depression 16 extending in the direction of the minor axis of the cover. Lateral depressions 18 are arranged at the sides of the depression 16 to receive the ends of the handle 19 which are welded therein as indicated at 20.

The edges 21 of the central portion of the handle 19 are bent outwardly in order to be more easily grasped. Near each end of the handle is formed a T-slot 22, beneath which are sockets 23 formed by the lower portions of the depressions 18 for receiving the heads 24 of the bolts 25. The heads 24 of the bolts 25 are first inserted in the widest part of the T-slots 22 in an inclined position and then the bolts are turned upright and the heads are moved back into the sockets 23 with the shanks fitting the narrower portion of the T-slot. These bolts 25 extend outwardly through yokes 26 of well known form and are screw threaded at their outer ends, as at 27, for the reception of nuts 28.

The metal between the flange 14 and the depressed portion 16 of the manhole cover-plate is shaped to form a substantially annular hollow rib 17, which is connected and reinforced centrally by means of the handle 19, thus strengthening the cover-plate considerably.

Having sockets formed on the outside of the cover-plate for receiving the heads of the bolts enables us to use any kind of stock bolt, without having to use bolts of special form, and obviates the necessity of punching holes in the cover-plates, thereby avoiding leakage and strengthening the cover-plate.

In forming manhole cover-plates in this manner, we are able to use a thinner material, and, at the same time, to make a structure which is as rigid as thicker ones now in use.

While we have shown our invention in but one form, it will be obvious to those skilled in the art that it is not so limited, but is susceptible of various other changes and modifications without departing from the spirit thereof, and we desire, therefore, that only

such limitations shall be placed thereupon as are imposed by the prior art or as are specifically set forth in the appended claims.

Having thus described our invention what we claim as new and desire to secure by Letters Patent is:

1. A closure device comprising an imperforate cover-plate, having a flanged edge, a depressed central portion, a hollow rib between the central depressed portion and the flanged edge, and recesses formed in the hollow rib at opposite sides of the depressed portion, and a handle extending across the depression and having its ends seated in the recesses and welded to the cover-plate, said handle being disposed in substantially the plane of the rib.

2. A closure device comprising an imperforate cover-plate, having a flanged edge, a depressed central portion, a rib between the flanged edge and the depressed central portion, recesses formed in the rib at opposite sides of the depressed portion, and a handle extending across the depression and having its ends seated in the recesses and welded to the cover-plate, said handle having T-slots extending therethrough near each end, said handle being disposed in substantially the plane of the rib.

3. In a device of the class described, the combination of an imperforate cover-plate,

having a flanged edge, a depressed central portion, a hollow rib between the flanged edge and the depressed central portion, and recesses and sockets formed in the rib, at opposite sides of the depression, and a handle extending across the depression and having its ends seated in the recesses and welded to the cover-plate, said handle having T-slots extending therethrough near each end and in registry with the sockets formed in the hollow rib for the reception of clamping bolts, said handle being disposed in substantially the plane of the rib.

4. A man-hole closure comprising an imperforate cover; having a flange providing a boundary seat, a dome portion extending outwardly from the seat side of the flange, a depression extending transversely off the dome portion, opposed depressions in the dome portion and extending laterally of the first depression, and a handle having its ends fitting in the lateral depressions and welded to the cover, said handle being provided with bolt holding means, said handle being disposed in substantially the plane of the dome portion.

In testimony whereof I hereunto affix my signature this 16th day of May, 1925.

JOSEPH H. DILLON.

In testimony whereof I hereunto affix my signature this 16th day of May, 1925.

HOWARD H. FAIRWEATHER.
